UNITED STATES PATENT OFFICE.

ROBBERT B. CLEMENT, OF CRAYNEVILLE, ASSIGNOR OF ONE-HALF TO
L. W. CRUCE, OF MARION, KENTUCKY.

WAGON-TONGUE SUPPORT.

SPECIFICATION forming part of Letters Patent No. 540,721, dated June 11, 1895.

Application filed January 31, 1895. Serial No. 536,868. (No model.)

To all whom it may concern:

Be it known that I, ROBBERT B. CLEMENT, a citizen of the United States, residing at Crayneville, in the county of Crittenden and 5 State of Kentucky, have invented a new and useful Wagon-Tongue Support, of which the following is a specification.

This invention relates to an improvement in that class of wagon tongue supports which 10 are hinged to the under side of the tongue, and capable of swinging so as to lie parallel therewith, or at right-angles thereto. These devices are generally associated with a suitable keeper on the tongue, whereby they are 15 held parallel therewith; also in some cases they are formed of two bars or legs which are capable of swinging apart or spreading, so as to support the tongue with greater stability. It is to this latter kind that my invention is 20 especially related, and the principal object is to provide a device having two arms with a normal tendency to spread, so that when released from the keeper they will automatically spread and attain the object of the device.

25 To this end the invention consists in two legs having a normal tendency to spread, and hinged to the under side of the tongue. The tongue is provided with a box-like keeper, which receives the free ends of the legs, and 30 which holds them parallel with the tongue while the device is not in use.

In the drawings, Figure 1 represents a perspective view showing a tongue supplied with my improvements and showing the tongue 35 turned bottom upward, to the end that the invention be better illustrated. Fig. 2 is a cross-section of the tongue when in its normal position and looking toward the support, which is shown to be actively engaged. Fig. 3 is a 40 detail section taken through the legs and showing the springs for giving them their normal tendency. Fig. 4 is a perspective view of a tongue supplied with a modification of my improvements, the tongue being shown to 45 be reversed, as in Fig. 1. Fig. 5 is a detail perspective view of the hinge.

Referring to Figs. 1, 2 and 3, the reference 50 numeral 1 indicates the tongue to which my improvements are shown as supplied, and which may be of any kind. Rigidly secured to the under side of the tongue, and near the

front extremity thereof is the plate 2, which forms one member of a hinge, whereby the supporting arms are secured to the tongue.

3 indicates the remaining member of the 55 hinge, and this is hingedly joined to the plate 2, and is a socket and consists of a single casting, and is perforated for bolts 5 and 6. These bolts are three in number. The middle bolt 5 is provided to receive a spring for spreading 60 the legs, as will be described hereinafter. The end bolts 6 pivotally mount the legs 7 in the socket of the hinge.

The legs 7 are of a length which will make them capable of supporting the tongue 1 in 65 the proper horizontal position. 8 indicates the spring for actuating these legs, and this is formed of a single piece of spring wire, having a coil 9 at its middle, the same embracing the bolt 5, while the ends or terminals 70 of the spring project outwardly, and are seated within recesses 10, in the respective arms 7. These terminals of the spring 8 have a normal tendency to part, and by these means the arms are given a like tendency. 75

The free ends of the legs 7 are tapered slightly at their outer sides, their inner or contiguous sides being plain, so that they will lie snugly against each other. These ends are held against the tongue by means of a keeper 80 11, which consists of an integral plate of metal bent to comprise a forwardly projecting tongue 12, whereby it may be secured to the tongue, and a rearwardly opening box-like portion 13, which receives the free ends of 85 the legs 7. The keeper is rigidly secured to the tongue or pole and forms a longitudinal socket, and is provided intermediate of its sides with a slot or opening, communicating with the socket, and permitting the legs to be 90 placed therein. Thus it will be seen that the legs, when it is desired to connect them to the keeper, should be moved to lie snugly against each other, after which they may be passed through the slot 14. When this has been 95 done, the spring 8 may be allowed to expand or spread the arms, which will cause them to lie in the respective sides of the box 13, so that they will not be liable to accidental displacement. 100

It will be understood, that the arms are to be held by the keeper 13, when they are not

being used to support the tongue, and when it is desired that they be out of the way as much as possible. When, however, it is desired to support the tongue, the arms should 5 be disengaged from the keeper and allowed to drop in the position of Fig. 2, whereupon their free ends will rest upon the ground and effectually support the tongue. It will be observed that the legs will automatically spread 10 and are arranged at opposite sides of the tongue, which will result in a far more effectual support of the tongue than otherwise arranged.

The modification of Fig. 4 consists of two 15 arms 15, similar in function to the arms 7, and formed of an integral spring bar. The bar composing the arms 15 is twisted together spirally, as shown at 16, at the middle thereof may be formed a loop 17, which is received by 20 the loop 18 of the metallic plate 19. This plate 19 is rigidly secured to the under side of the tongue at a point commensurate with the point to which the plate 2 of Figs. 1, 2 and 3 is secured. Thus it will be seen that 25 the arms 15 are pivotally mounted on the tongue, so as to be capable of swinging freely thereon, as has been explained in connection with Figs. 1, 2 and 3, and to hold the arms 15, a keeper 20 is provided, which keeper is the 30 equivalent in construction and function of the keeper 11, and which co-operates with the arms 15 as the said keeper 11 co-operates with the legs 7.

Each of the forms of my invention illustrated in the drawings is regarded as having 35 almost the same degree of efficiency. If, however, there is any advantage, it is thought to lie in the form of Figs. 1, 2 and 3, since it may be difficult and expensive to construct the 40 arms 15 after the manner illustrated in Fig. 4.

It will be observed, that the device may be attached to wagon tongues without encumbering them, or rendering their use disad-

vantageous, since, when the support is folded, it will lie snugly against the pole, and be practically a part thereof.

Various changes in the form, proportion, and the minor details of construction may be resorted to without departing from the principle or sacrificing any of the advantages of this invention.

Having thus described the invention, what I claim is—

1. In a tongue support, the combination of a tongue provided on its lower face with a keeper having a longitudinally disposed socket, and provided intermediate of its sides with a slot or opening communicating with the same, and a pair of outwardly springing or separating legs, hinged to the pole and adapted to be compressed and to have their lower ends pass through the slot or opening of the keeper, whereby the resiliency of the legs will hold them in the socket of the keeper away from the opening or slot thereof, substantially as described.

2. In a tongue support, the combination of a tongue provided on its lower face with a rigid longitudinally disposed keeper provided intermediate of its sides with an entrance slot or opening, a hinge secured at one leaf to the lower face of the tongue, and having its other leaf provided with a socket, a pair of separable legs pivoted in the socket of the hinge and having their other ends arranged in the keeper, and a spring interposed between the legs and adapted to spread the same and hold them in engagement with the keeper, substantially as described.

In testimony that I claim the foregoing as my own I have hereto affixed my signature in the presence of two witnesses.

ROBBERT B. CLEMENT.
